A. L. RUSSELL AND C. E. GRUSH,
UPPER STRETCHING MACHINE.
APPLICATION FILED JULY 17, 1916. RENEWED JULY 6, 1918.

1,313,918.

Patented Aug. 26, 1919.

INVENTOR.

Arthur L. Russell.
Charles E. Brush.

UNITED STATES PATENT OFFICE.

ARTHUR L. RUSSELL, OF BOSTON, AND CHARLES E. GRUSH, OF BEVERLY, MASSACHUSETTS, ASSIGNORS, BY MESNE ASSIGNMENTS, TO UNITED SHOE MACHINERY CORPORATION, OF PATERSON, NEW JERSEY, A CORPORATION OF NEW JERSEY.

UPPER-STRETCHING MACHINE.

1,313,918.

Specification of Letters Patent. Patented Aug. 26, 1919.

Application filed July 17, 1916, Serial No. 109,664. Renewed July 6, 1918. Serial No. 243,708.

To all whom it may concern:

Be it known that we, ARTHUR L. RUSSELL and CHARLES E. GRUSH, citizens of the United States, residing at Boston, in the 5 county of Suffolk, State of Massachusetts, and at Beverly, in the county of Essex and State of Massachusetts, respectively, have invented certain Improvements in Upper-Stretching Machines, of which the following description, in connection with the accompanying drawings, in a specification, like reference characters on the drawings indicating like parts in the several figures.

This invention relates to machines for 15 stretching leather and in particular to machines for operating upon upper leather for use in boots and shoes to effect improvements in fit, facilitate the lasting operation, and reduce the cost of manufacture.

20 The invention embodies certain improvements in the machine for applying local stretching to the interior portions of stock progressively, by repeated operations of the machine, disclosed in our co-pending application Ser. No. 827,609, filed March 27, 1914, and has for one of its objects to simplify the mechanism while retaining important advantages of that machine. The present invention contemplates the employment 25 of mechanism for subjecting a small area only of the stock to tension at a time, and at the next operation subjecting the same, or an adjacent area, to tension during the continuous running of the machine, so that interior portions of the upper may be 30 permanently stretched and thus be made to fit the high and low portions of lasts, and to truly conform to the varying curvature of their surfaces.

35 40 The local stretching of the stock is preferably performed by two pincers whose jaws are spaced apart an appropriate distance and are adapted to seize adjacent portions of stock, to move apart for stretching the stock, and to then retract, and also to separate and release the stock. These operations may be repeated as many times as desired, either at the same point or at different points on the sheet.

45 50 Conveniently, and as herein shown, the pincers consist of two jaws pivotally connected with links which are joined by a common pivot to a reciprocatory plunger located on one side of a work table, and two

coöperating jaws which extend through an opening in the table and are supported by links pivotally sustained from a rigid extension of the table and located on the opposite side of the latter. The links for sustaining the first-mentioned jaws have ends 55 extending beyond their pivots which are spring-pressed to hold the jaws normally apart a desired distance, and the coöperating jaws are maintained, yieldingly and adjustably, in proper relation to the first-named 60 jaws. When the plunger is depressed the adjacent pincers will first seize the stock and then be caused to moved apart to stretch the stock; and when the plunger is moved 65 reversely the pincers will first approach each other, and the jaws of each pincer will then separate to release the stock. The described operations may be repeated, as many 70 times as desired, upon the same, or adjacent portions of the stock, until the latter 75 has been stretched at the places, and to the extent required, to fit properly the high and low portions of a last, or the varying curvatures of a last or any other irregularly shaped form. Preferably the plunger 80 which supports and actuates the first-mentioned pincer jaws is reciprocated by a cam having a path so designed as to impart a slow pulling movement to the pincers through about one-half the cycle to seize and 85 stretch the stock, then a dwell during one-fourth of the cycle to hold the stock under tension so as to render the stretching permanent, and a quick return for the remaining one-fourth of the cycle to lift the 90 jaws from the stock rapidly and thus lessen the inward drag of the jaws on the stock.

The several features of invention embodied in the illustrated mechanism, including important details of construction and 95 combinations of parts, will be hereinafter more particularly described and will be pointed out in the claims.

In the drawings:

The figure shows, in side elevation, partly 100 sectional, a machine embodying the present invention.

The machine frame 1 has a base 3 which supports the internally threaded hub 9 of a hand wheel 7, the hub 9 being formed with 105 an external groove 10 which receives a lug 13 projecting from a plate which is clamped to the base. A work table 12 has a base 11

which is rigid with a screw stem 5 having a coarse thread, and fitting the internal thread of the hub 9. The stem 5 has a vertical slot 50 which receives a guide pin 6, projecting rigidly from the frame base, said parts serving to prevent rotation of the screw stem. By turning the hand wheel the screw stem will be caused to feed up or down, according to the direction of rotation, and the work table may thus be adjusted to locate its work-receiving surface in the desired relation to the plane of the pincer jaw. During the rotation of the hand wheel the engagement of the lug 13 with the groove 10 will retain the hand wheel against vertical movement and thereafter will hold it adjusted.

The upper part of the machine frame supports suitable bearings for a shaft carrying a pulley 14 which may receive power, through a belt, from a suitable source. The pulley shaft carries a disk having a crank pin 16 thereon which runs in a cam groove 18, in a cam block 19. The cam block operates a plunger 22 which is guided for reciprocating movements by a plate 24, bolted to the frame, and by a stem 20, rigid with the upper part of the cam block, and guided suitably by a plate 21 which is likewise bolted to the frame. There is a yielding lost motion connection between the stem and plunger, as shown in the drawings, and the plunger 22 sustains, by a pivot 26, the two jaw-supporting links or arms 28, 28, which respectively sustain, through pivots, each of the uppermost pincer jaws 32, 32, whose lower faces have sufficient friction quality to maintain engagement with the stock. The links 28 have divergently extending upper end portions 29 normally acted upon by a spring 30 which holds the jaws normally pressed toward each other and against the stop 33 and thereby maintains the jaws 32, 32 spaced a suitable distance from each other, and leaf springs 34, 34 are secured to the arms 28, 28 and bear at their free ends against the jaws 32, 32 so as to hold them yieldingly with their faces in substantial parallelism with the faces of the other pincer jaws 36, 36.

The jaws 36, 36 which, if they are to engage the inner side of the leather stock, preferably have their faces roughened slightly to prevent slipping, project through an opening 37 in the work table 12, and are supported by links 38, 38 whose lower ends are sustained by a single pivot 40 from the table base 11. The links 38 are provided with aligned horizontal perforations through which passes an adjusting rod 42, having at its outer free end a knurled or roughened handle 43. The rod is encircled by a spring 41 that holds jaws 36, 36 normally apart and the rod has right and left hand external screw threads engaging internal screw threads in

two spaced nuts 44, 44 which are provided with pins 48, 48, moving in guiding slots formed in two sleeves 46, 46. These sleeves are bored to receive the nuts 44 and are also formed at their inner ends with forked portions which embrace the links 38. Spiral springs 49 are located in the bores of the sleeves between the inner ends of the nuts and the bottoms of said bores and hold the jaws normally in the position shown until the stock has been gripped between the upper and the lower jaws. Then the springs yield to allow the jaws to separate to stretch the stock. The springs 49 return the jaws to their initial position after each stretching operation. By turning the handle 43 the tension of the springs may be adjusted to insure different degrees of gripping force before the pincers begin to separate to stretch the stock.

The cam groove 18 is formed with a substantially flat, or horizontal portion 18^a along which the crank pin 16 acts during about one-half of the cycle, which moves the plunger 22 and pincer jaws 32, 32 downwardly to clamp the work against the jaws 36, 36 and, by continued downward movement, causes the pincers to move apart and stretch the stock. The maximum movement of the pincers to stretch the stock occurs at the time that the pin 16 reaches its lowest point. Thereafter the pin enters the substantially concentric portion 18^b of the cam groove, which produces a dwell, thus maintaining the stock stretched for an interval of time which tends to render the stretching permanent. Thereafter the crank pin reaches the end of the curved portion 18^b of the groove, and for the remaining one-quarter of its stroke the crank pin acts to quickly raise the plunger 22, thus causing a rapid release of the stock from the gripping action of the pincers. This is especially advantageous in that it tends to prevent any drag of the pincer jaws over the stock during the inward movement of the jaws, as they are lifted instantly from the work.

This machine is well adapted for stretching different portions of stock interiorly of the edges thereof, and especially those parts of a shoe upper which are fitted to the high and low portions of a last, and by the machine toe caps or the tip portions of shoe uppers may be stretched to conform truly to the convexity or concavity of a last so that the parts may be cut somewhat smaller than at present, and may be made to fit the toe of the last with less manipulation in the pulling and lasting operations, and will be more convenient to engage by the toe gripper of a pulling-over machine.

For adjusting the machine, the workman first rotates the hand wheel 7 to raise or lower the work supporting table 12 and the jaws 36, 36 so as to present the surfaces of the table and these jaws in desired vertical

relation to the gripping faces of the jaws 32, 32, the extent to which the pincers move apart for stretching the stock being determined by the elevation of the lower jaws 5 and the table because the stroke of the cam and therefore of the upper jaws is constant. The hand wheel 43 is also turned, to the right or to the left, effecting an inward or outward movement of the jaws 36 to properly align them with the jaws 32.

In the use of the machine a piece of leather stock is placed upon the work table with the portion which is to be stretched located between the pincer jaws. Power being then applied, through a belt or other suitable means, to the pulley 14 and the crank pin being at its highest point, said crank pin first causes a depression of the plunger carrying the jaws 32, 32, the stock 20 being gripped between these and the coöperating jaws, and further movement of the plunger effects a separation of the pincers to stretch the stock, with a suitable dwell at the end of the stretching movement, and therefore 25 after a lifting of the pincer jaws 32 to release the stock. If the machine continues to operate while the stock remains in one position the same area may be subjected to a plurality 30 of successive tensioning operations, until a desired amount of stretching has been attained. The operator may then move the stock to a different position and subject a different area to as many successive tensioning impulses of the machine as may be desired. The upper may not only be stretched along parallel lines back and forth by feeding the stock properly by hand during the 35 intervals between the pulling movements of the pincers, but the work may be turned so as to obtain successive stretching effects in 40 different directions, as when shaping a toe cap to fit over the toe end of a last. In shaping an upper to fit the last back of a high toe to prevent bridging from the toe to 45 the instep a stretching in a direction lengthwise of the last only is required to provide an amount of fullness sufficient to permit the upper to lay into the hollow of the last. Similarly in shaping shank portions of a 50 shoe upper where it is desired to make the leather fit a narrow shank last the direction of stretching will be mainly lengthwise and may be made greater at the edge of the stock and gradually diminishing at a point remote 55 from the edge. This gradation of the stretching action is obtainable by feeding the stock along by hand at the proper rate during the continuous operation of the machine, the rate of feed being increased as the 60 operation progresses farther from the edge of the stock.

In the stretching and retracting movements of the pincers the links 28, 38 for the two pincers constitute in effect two toggle joints, having movements in opposite direc-

tions, toward and from each other. The fact that a pin 26 pivotally supports one link of each toggle, while a pin 40 pivotally supports the other link of each toggle, and that said pins are located in line with the center of the reciprocating plunger 22 insures uniformity of movement of the jaws of the pincers as they move apart to stretch the stock, and move reversely to release the stock. This constitutes a very simple and efficient mechanical construction for operating the stretching pincers, and we regard it as a very important feature of the present invention. Use of a table, while convenient, is not necessary and the operating plunger 80 may be connected with the lower pair of toggle members instead of the upper pair if desired. It is contemplated that the stock stretching movements shall be comparatively short and that the machine shall usually be 85 run at a speed permitting the stock to recover itself more or less, or react partially or completely as its elasticity will cause it to do, between successive stretching actions on the same portion of the stock to avoid a 90 cumulative effect liable to produce rupture of the stock.

The work engaging faces of the jaws are preferably of large area compared with the space between the jaws so that there is a 95 very substantial compressing or beating of the stock effected by the jaws, as the stock is moved progressively between them, in addition to the stretching of the stock. This organization will distend stock materially 100 without opening the grain of the stock to any marked degree.

Having described our invention, what we claim as new and desire to secure by Letters Patent of the United States is:

105

1. A machine of the class described having, in combination, a work support, pincers arranged for engaging an interior portion of stock, and mechanism to cause said pincers to seize the stock, to move relatively for 110 stretching it, to cease the stretching movement and hold the stock under tension, and to release the stock.

2. A machine of the class described having, in combination, a work support, pincers arranged for engaging interior portions of stock on said work support, and actuating means for the pincers to cause them to seize the stock, to move apart for stretching it, to cease the stretching movement and hold the 120 stock under tension, and to release the stock.

3. In a machine of the class described, the combination with a work support, of pincers for engaging stock at separated points located within and removed from the edges of the 125 stock, means for imparting positive movements to the pincers to seize the stock and stretch it, and yielding means to cause the pincers to release the stock and return to initial position.

130

4. In a machine of the class described, the combination with a work support, of pincers for engaging stock on said support, toggle members for supporting a jaw of each pincer 5 on each side of said support, and actuating means for the toggles to cause the pincers to seize, stretch and release the stock.
5. In a machine of the class described, the combination with a work support, of pincers 10 for engaging stock on said support, toggle members supporting a jaw of each pincer on one side of the stock, toggle members supporting another jaw of each pincer on the opposite side of the stock, and actuating 15 means for the toggles to cause the jaws to seize stock, to move apart to stretch it, and to move reversely to release it.
6. In a machine of the class described, the combination with a work support, of toggle 20 members sustaining two pincer jaws on one side of said support, toggle members connected with two coöperating pincer jaws on the opposite side of said support, and a reciprocating member having pivotal connection 25 with said last-named toggle members and arranged for actuating the toggles to cause the pincers to seize and stretch the stock.
7. In a machine of the class described, the combination with a work support, of pincers 30 arranged to engage interior portions of stock on the support, toggles having connection with the pincers' jaws on opposite sides of said support, and actuating means for the 35 toggles to cause the pincers to seize, stretch and release the stock.
8. In a machine of the class described, the combination with a work support, of pincers having jaws arranged to engage the two opposite sides of stock at spaced points within 40 its edges, toggle members sustained from a common pivot and carrying the pincer jaws for operating on one side of the stock, other toggle members sustained from a single 45 pivot and carrying the pincer jaws for operation on the opposite side of the stock, and actuating means for the toggles to cause the pincers to seize and stretch stock.
9. In a machine of the class described, the combination with a work support, of pincers 50 for seizing and stretching stock thereon and comprising jaws sustained above and below said support, means for adjusting said support relative to the plane of the upper jaws, 55 and actuating means for the pincers.
10. In a machine of the class described, the combination with a work support, of pincers for seizing and stretching stock thereon and comprising jaws sustained above 60 said support, coöperating jaws carried by the work support, and means for adjusting said jaws and work support with relation to the plane of the faces of the first-mentioned jaws.
- 65 11. In a machine of the class described,
- the combination with a work support, of pincers having jaws arranged to engage opposite sides of stock at spaced points, actuating means to cause the pincers to seize and stretch the stock, and means for adjusting 70 the jaws on one side of the stock relatively to the jaws on the opposite side of the stock in a plane parallel with the stock-engaging faces of the jaws.
12. In a machine of the class described, 75 the combination with a work support, of pincers having jaws arranged to engage opposite sides of stock at spaced points, actuating means to cause the pincers to seize and stretch the stock, and means for adjusting 80 the jaws on one side of the stock relatively to the jaws on the opposite side of the stock in planes parallel with and perpendicular to the stock-engaging faces of the jaws.
13. In a machine of the class described, 85 the combination with a work support, of pincers having jaws for engaging stock at spaced points thereon, adjusting means to move the jaws on one side of the stock toward or from each other in the plane of 90 the stock-engaging faces of said jaws, and actuating means to cause the pincers to seize and stretch the stock.
14. In a machine of the class described, the combination with a work support, of 95 pincers having jaws for engaging stock thereon, pivotal means to support the jaws on one side of the stock, an adjusting rod, and yielding means between said rod and jaws for effecting movements of said jaws 100 in opposite directions in a plane parallel with the stock-engaging faces of the jaws.
15. In a machine of the class described, the combination with a work support, of pincers having jaws for engaging stock 105 thereon, links supporting the pincer jaws on one side of the stock, and adjusting devices for said jaws comprising a rod having right and left hand threads thereon, nuts engaging said threads, sleeves engaging opposite 110 sides of said links, and springs located between said nuts and sleeves.
16. In a machine of the class described, the combination with a work support, of pincers having jaws arranged to engage opposite sides of stock, and actuating means 115 for the pincers, including toggles arranged to cause the pincers to seize the stock, to move apart and stretch it, and to move reversely and release it.
17. In a machine of the class described, the combination with a work support, of pincers having jaws arranged to engage opposite sides of stock, toggle members for supporting the jaws on one side of the stock, 125 pivotal means connecting said jaws and toggle members, and yielding means to maintain the stock-engaging faces of said jaws in proper relation with the plane of the stock.

18. In a machine of the class described, the combination with a work support, of pincers for seizing and engaging stock, toggle members supporting coöoperating pincer 50
5 jaws on opposite sides of said support, a plunger pivotally connected with the toggle members above the support, a cam connected with said plunger and having a path designed to impart first a slow movement to 55
10 the toggles for causing the pincers to seize the stock and move apart to stretch it, then a dwell to hold the stock under tension, and finally a quick movement to release the stock, a crank pin moving in said path, and actuating means for said crank pin.
- 15 19. A machine of the class described having, in combination, a pair of spaced pincers having jaws for engaging stock, pivotal means for supporting the jaws upon one 60
20 side of the stock, a plunger having pivotal connection with the jaws upon the opposite side of the stock, and means for reciprocating said plunger to cause said pincers to engage the stock, to spread apart for 65
25 stretching it, and to move reversely for releasing the stock.
20. In a machine of the class described, two reversely flexed pairs of toggles the members of which are disconnected at their 70
30 knuckles and provided with gripping faces, and means for relatively moving the upper members of the toggles toward the lower members to effect gripping of stock between the upper and lower members and then 75
35 stretching of the stock between the respective grippers by further flexing of the toggles.
21. In a machine of the class described, two reversely flexed pairs of toggles the members of which are disconnected at their 80
40 knuckles and provided with gripping faces, and means for relatively moving the upper members of the toggles toward the lower members to effect gripping of stock between the upper and lower members and then 85
45 stretching of the stock between the respective
